UNITED STATES PATENT OFFICE.

HARRY J. HICK, OF ALLIANCE, OHIO, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,118,008.

Specification of Letters Patent.

Patented Nov. 24, 1914.

Application filed December 29, 1909, Serial No. 535,455. Renewed March 28, 1914. Serial No. 828,095.

To all whom it may concern:

Be it known that I, HARRY J. HICK, a citizen of the United States, residing at Alliance, in the county of Stark and State 5 of Ohio, have invented certain new and useful Improvements in and Relating to Filing Appliances, of which the following is a specification.

This invention relates to a filing appliance having a plurality of plates or leaves which support papers or articles in classified order.

For the purpose of illustration, I have in the accompanying drawings shown, and 15 herein described, one form of filing appliance embodying my invention.

Figure 1 is a perspective view of a filing appliance embodying my invention, the appliance being shown as adapted to or supported in the drawer of a desk. Fig. 2 is a side elevation of the filing appliance, the drawer being in section. Fig. 3 is a view 20 similar to Fig. 2, but showing some of the leaves in elevated position. Fig. 4 is a fragmentary top plan view of the appliance. Fig. 5 is a section on the line 5—5 of Fig. 3, showing the filing appliance in elevation. Fig. 6 is a detail view partly in section showing the spring and base for supporting 25 and operating the leaves of the appliance. Figs. 7, 8 and 9 are fragmentary detail views of the leaves and their connecting means, parts thereof being shown in section. Fig. 10 is a fragmentary perspective 30 view of a leaf, somewhat enlarged. Figs. 35 11 and 12 are enlarged perspective views of the hinge plates.

In the drawings 1 indicates a filing appliance comprising a plurality of leaves 1^a. 40 The appliance, purely for illustrative purposes, is shown as combined with the drawer *a* of a desk *A* which operates as a casing and support for the appliance. The filing appliance 1 may be and preferably is 45 removably supported in the drawer whereby it may be removed to a fireproof vault or place of safe keeping at will. Each of the leaves 1^a comprises a back or plate 1^b formed from sheet metal. Strips 1^c, 1^c, 50 extend along its opposite side edges to strengthen the plate transversely and form the outer walls of the outermost filing spaces or divisions on each side of the leaf. Strips 1^d are arranged preferably on oppo-

site sides of each plate or back and serve as 55 division and separating elements. Clamping devices, of any well known form, such as spring clips 1^e for securing papers to the leaf or plate, may be arranged in the pockets or division spaces formed by the strips 1^c. 60

Along the lower longitudinal edge of each leaf the plate or metal sheet 1^b is extended and pressed or shaped into a hollow bar 1^d', preferably rectangular in shape, which extends continuously, in the illustrated embodiment of my invention, from side to side of the plate 1^b. The end 1^b' of the metal sheet is preferably bent back upon the sheet to lie flat against the adjacent face of the sheet 1^b, and is preferably secured thereto by rivets 1^f. The outer or free edge of each back 1^b is preferably bent over on itself, as shown at 1^g, to form a smooth edge for the hands to grasp in operating the leaves. 75

2 indicate connections operating to connect the leaves together along their lower edges and to permit them to be raised and lowered one by one into the positions illustrated in Figs. 1, 2 and 3. The connections 80 2 comprise metal hinge plates 3, 4, preferably of sheet metal, carried alternately by the leaves. The plates 3 and 4 are each formed into the shape of or pressed around the hollow longitudinal bar 1^d' of a leaf 1^a. 85 The free ends of each of said hinge plates are arranged to lie flat against the opposite faces of the adjacent leaf or back 1^b and are preferably secured thereto by the same rivets 1^f, heretofore referred to in connection with the securing of the end 1^b' of the leaf or sheet. These hinge plates 3, 4 are 90 of two forms, one of each being employed to make a complete hinge connection between the adjacent edges of adjoining leaves. 95 Each of the hinge plates 3 is formed with two alined and spaced hinge loops or hollow end bars 3^a, 3^a at either lower corner thereof. Each of the hinge plates 4 is formed with a hinge loop 4^a at either lower corner thereof. 100 Each of the hinge loops 4^a of each plate 4 lies between and alines with the adjacent pair of hinge loops 3^a of an adjoining hinge plate 3. A pintle 5, preferably formed from a strip of sheet metal rolled into cylindrical 105 hollow shape, as shown in Figs. 8 and 9, serves to connect the alined hinge loops and complete the hinge connection. I prefer-

ably provide the appliance with two sets of hinge connections 2 each arranged near the opposite ends of the hollow bars 1^a.

6 indicates a supporting base carried by the drawer *a*. The base 6 corresponds in size to the outside dimensions of the lowermost leaf 1^a of the appliance 1 and is provided with upwardly extending flanges 6^a along its opposite edges within which the appliance 1 closely fits.

From Figs. 2 and 3 it will be understood that as each of the leaves 1^a are operated from a horizontal to a vertical position those remaining in a horizontal position move outwardly relatively to the drawer *a* or in the direction in which their free ends extend; while those leaves raised to the vertical position move downwardly. To facilitate this movement suitable guides 7 and 8 are provided. The guides 7 consist of channels 7^a formed in the bottom of the drawer and ribs 7^b carried by the lower face of the base 6, while the guides 8 consist of plates 8^a secured to the vertical side of the drawer *a* and bearings 8^b carried by the uppermost leaf of the set of leaves 1^a. The guides 7 also operate to prevent relative movement between the filing appliance and the drawer in its longitudinal direction during the opening and closing thereof.

9 indicates a spring connected at one end to an eye or hook 9^a fixed to the drawer *a*. The opposite end of the spring 9 is connected to the under side of the base 6. This spring operates to return the base 6 and leaves 1^a to normal position as the leaves are moved from the vertical to the horizontal position.

As shown in the drawings the uppermost leaf of the filing appliance may be provided with an index sheet 10.

As a result of my improvements, a filing appliance of economical construction, light weight, strength and durability, as well as one economical of space is obtained.

To those skilled in the art of making apparatus of the class described, many alterations in constructions and widely differing embodiments and applications of my invention will suggest themselves, without departing from the spirit and scope thereof. My disclosures and the description herein are purely illustrative, and are not intended to be in any sense limiting.

55 What I claim is:

1. A leaf for a filing appliance, formed from sheet metal and having its lower longitudinal edge bent back upon itself to form a hollow bar, in combination with a hinge plate connected to said bar intermediate its opposite ends and adapted to form one part of a hinge or pivot to permit the leaf to swing from one position to another.

2. A filing appliance comprising a series 65 of leaves, each formed from sheet metal and

having its lower longitudinal edge bent back upon itself to form a hollow rectangular shaped bar, and hinge devices between adjoining leaves, each device being secured to the adjacent hinge bar intermediate between its ends.

3. A leaf for a filing appliance, formed from sheet metal and formed along or near its lower longitudinal edge into a hollow rectangular-shaped bar, and the end of the 75 said leaf being bent to lie flat against the said back and means for securing said end thereto.

4. In a filing appliance, a leaf for holding papers formed from sheet metal, the metal 80 along the lower portion of the leaf being extended and bent into a longitudinal hollow bar which extends an equal distance to either side of the leaf, the bottom, side and top walls of the bar being arranged at 85 right angles to each other, in combination with a hinge plate provided with a loop for receiving a pivot to permit the pivotal connection of said leaf with another leaf, the said hinge plate having walls arranged at 90 right angles to each other and snugly fitting the bottom, side and top walls of said hollow bar.

5. In a filing appliance, a leaf for holding papers formed from sheet metal, the metal 95 along the lower portion of the leaf being extended and bent into a longitudinal hollow bar which extends an equal distance to either side of the leaf, the bottom, side and top walls of the bar being arranged at right 100 angles to each other, in combination with a hinge plate provided with a loop for receiving a pivot to permit the pivotal connection of said leaf with another leaf, the said hinge plate having walls arranged at 105 right angles to each other and snugly fitting the bottom, side and top walls of said hollow bar, and means for securing the free edge of the sheet metal and the opposite ends of the hinge plate to the adjacent leaf. 110

6. In a filing appliance, a leaf for holding papers formed from sheet metal, the metal along the lower portion of the leaf being extended and bent into a longitudinal hollow bar which extends an equal distance to either 115 side of the leaf, the bottom, side and top walls of the bar being arranged at right angles to each other, in combination with a hinge plate provided with a loop for receiving a pivot to permit the pivotal connection of said leaf with another leaf, the said hinge plate having walls arranged at right 120 angles to each other and snugly fitting the bottom, side and top walls of said hollow bar, and means for securing the free 125 edge of the sheet metal and the opposite ends of the hinge plate to the adjacent leaf, the loop of the hinge plate being at the lower corner of the adjacent hinge bar.

7. In a filing appliance, the combination 130

of a series of leaves each formed from sheet metal and provided along its lower longitudinal edge with a hollow bar, and connections between the bars for hingedly connecting the leaves together, the said connections comprising metal hinge plates each formed around an adjacent hollow bar and portions of the plate intermediate its ends being provided with hinge loops arranged to 5 aline with the hinge loops of the hinge plates carried by adjoining leaves, and pintles extending through said hinge loops.

8. In a filing appliance, the combination 10 of a series of leaves, each formed from sheet metal to form a back, the metal being extended along the lower longitudinal edge of the back and bent back on itself to form a hollow bar, and connections between the bars for hingedly connecting the leaves together, the said connections comprising metal hinge plates each formed around an adjacent hollow bar, and each having hinge loops along the opposite lower corners of 15 the hinge plates and arranged to aline with the hinge loops of the hinge plates carried by adjoining leaves, and pintles extending through said hinge loops for connecting the hinge plates together.

20

25

9. In a filing appliance, the combination 30 of a series of leaves each formed from sheet metal, the sheet metal being extended along the lower longitudinal edge of each leaf and bent back upon itself into a rectangular-shaped hollow bar, and connections between the bars of the leaves for hingedly connecting the leaves together, the said connections comprising metal hinge plates one for each hollow bar, extending around said hollow bars, and each having hinge loops along their opposite lower corners and arranged to aline 35 with the hinge loops of the plate carried by adjoining leaves, and pintles extending through said hinge loops for connecting the plates together, the opposite free ends of the metal hinge plates being bent to lie 40 flat against the opposite faces of the adjacent leaf, and means for securing the free edges of each metal hinge plate to the said leaf.

In testimony whereof I affix my signature, 45 in the presence of two witnesses.

HARRY J. HICK.
